UNITED STATES PATENT OFFICE.

WILLIAM J. TYNON, OF DE SOTO, ASSIGNOR TO OTTO BUEHRMANN, OF ST. LOUIS, MISSOURI.

DOOR-CHECK.

SPECIFICATION forming part of Letters Patent No. 537,250, dated April 9, 1895.

Application filed June 25, 1894. Serial No. 515,587. (No model.)

To all whom it may concern:

Be it known that I, WILLIAM J. TYNON, of the city of De Soto, Jefferson county, State of Missouri, have invented certain new and useful Improvements in Door-Stops, of which the following is a full, clear, and exact description, reference being had to the accompanying drawings, forming a part hereof.

My invention relates to improvements in door stops, and consists in a suitable casing, a spring-actuated plunger operating within said casing, a plunger operating within said plunger, and other details of construction that will be hereinafter described and claimed.

15 The object of my invention is to provide a door stop that will possess superior advantages in point of simplicity, durability and general efficiency.

A further object of my invention is to construct a door stop that may be operated, or thrown into or out of engagement by a slight movement of the foot.

In the drawings: Figure 1 is an edge elevation of a door, the same having my improved stop attached thereto. Fig. 2 is a vertical sectional view taken on the indicated line 2—2 of Fig. 1, and looking in the direction indicated by the arrow "A." Fig. 3 is a vertical cross-sectional view of my improved door stop. Fig. 4 is a cross-sectional view on the line 4—4 of Fig. 2. Fig. 5 is a cross-sectional view on the line 5—5 of Fig. 2. Fig. 6 is a cross-sectional view on the line 6—6 of Fig. 2.

Referring by numerals to the accompanying drawings, 1 indicates a door, to which (near the lower edge) is secured my improved door stop.

A plate 2, preferably rectangular in form and provided with a series of screw-holes 3, 40 has formed integral therewith and vertically positioned upon its outer face, an open ended cylindrical casing 4. The interior of the upper end of this casing is screw-threaded and adapted to receive an exteriorly screw-threaded cap 5, the same having a centrally located aperture 6 therein. An annular flange 7 is formed on the inner side of the bottom of this casing 4, and is adapted to serve as a guide for the vertically moving plunger 8, the same being located and operating within the cylindrical casing 4.

Extending from a point near the top of the cylindrical casing 4 to a point near the center thereof is a slot 9, its lower end terminating with a laterally formed notch, or slot 10.

55 The plunger 8 operating within the casing 4 is of a length and diameter less than that of said casing, is provided with a vertical bore, or recess, 11 extending from the top to a point below the longitudinal center of said 60 plunger, and also with a bead or flange 12 on its lowermost edge. The periphery of the upper end of this plunger 8 is screw-threaded and adapted to receive an interiorly screw-threaded cap 13. This cap is provided with 65 a centrally located aperture 14.

A plunger 15 in the form of a rod passes through the aperture 6 in the cap 5, and its lower end through the aperture 14 in the cap 13. The lower end of this plunger 15 is provided with an annular bead or flange 16 which effectually prevents said plunger from leaving the recess or bore 11 within the plunger 8. The upper end of this plunger 15 is provided with 70 a cap 17 held in position by a screw 18.

75 Formed integral with the body of the plunger 15, and at a point slightly below the longitudinal center thereof, is a disk, or annular flange, 19 of a diameter equal to the inner diameter of the casing 4. The object of this 80 flange 19 is to more firmly guide the plunger 15 in its movement, the range of motion of this flange 19 being from the cap 13 to the cap 5. A horizontally projecting pin or stop 20 is formed integral with this annular flange 85 19 and extends laterally through the slot 9 in the cylindrical casing 4. It projects a slight distance beyond the periphery of said casing 4.

A torsional coil-spring 21 surrounds the plunger 8, and has its upper end passed 90 through an aperture 22 in the annular flange 19. The lower end of this torsional spring 21 passes through one of a series of apertures 23 that are formed in the inwardly extending annular flange 7 on the lower end of the cylindrical casing 4. By having such a series of apertures the tension of said spring can be, to a certain extent, graduated or regulated.

An ordinary compression coil-spring 24 occupies the recess or bore 11 in the plunger 8, 100 and beneath the lower end of the plunger 15. An annular ring 25 is loosely mounted upon the

lower end of the plunger 8 immediately below the cylindrical casing 4. A rubber foot 26, preferably circular in form, surrounds the lower end of the plunger 8 and is securely held 5 thereon by means of the bead, or flange, 12.

By means of suitable screws passed through the apertures 3 in the plate 2, the stop is secured upon the door approximately in the position as shown in Fig. 1. In this figure the 10 plungers and rubber foot are shown in their normal position, or at an elevated point, said rubber foot being disengaged from the floor.

The operation is as follows: When it is desired to set or hold a door in any desired position, a person manually or pedally forces down the plunger 15. This necessarily moves the annular flange 19 downwardly, the pin 20 thereof sliding in the vertical slot 9. As soon as the rubber foot 26 contacts with the floor, and 15 the plunger 15 is pushed farther downward, the coil-springs 21 and 24 will be compressed. When the plunger 15 has reached the limit 20 of its downward movement, the pin 20 will be directly opposite the laterally positioned slot 25 or notch 10. By reason of the power stored in the torsionally bent spring 21, said pin 20 will be thrown into said lateral slot or notch, and in such a manner as to firmly and securely position the various parts in the desired 30 position, or as shown by dotted lines in Fig. 1. When in this position the rubber foot will be in close contact with the floor, the plunger 8 at its downward limit of movement, the springs 21 and 24 compressed, the plunger 15 35 at its limit of downward movement, the annular flange 19 thereof being adjacent the cap 13 of the plunger 8. Thus the door is firmly held in the required position. When it is desired to disengage the foot from the floor, the 40 pin 20 is thrown out of the lateral notch or slot 10 and into the vertical slot 9. The power stored within the springs 21 and 24 will cause the two plungers to reassume their normal position, as shown in Figs. 1, 2 and 3. The 45 office of the coil-spring 24 is to act directly upon the plunger 15, which, as soon as the bead or flange 16 comes in contact with the cap 13, will necessarily raise the plunger 8 carrying the foot 26. The coil-spring 21 ma-

terially assists in this operation, but the main object of said spring 21 is to guide the pin 20 of the flange 19 into the lateral notch or slot 10.

Thus it will be seen how I have provided a simple, durable and inexpensive door stop, one that is quickly and easily operated and efficient in use.

What I claim is—

1. A door stop, comprising a base-plate, a cylindrical casing formed integral with said base-plate, a vertically moving plunger operating within said casing and provided with a vertical bore or recess, a second plunger operating within said cylinder and within the recess or bore formed in the first mentioned plunger, a pin or lug positioned upon said last mentioned plunger and operating within a slot formed in the wall of the casing, a coil-spring interposed between the two plungers, and a torsionally bent spring positioned upon the first mentioned plunger.

2. In a door stop, the combination of a cylindrical casing, a plunger operating within said casing and having therein a vertical bore, a plunger adapted to enter the first mentioned plunger, a coil-spring interposed between said plungers and within the bore, a pin formed integral with the second plunger, said pin operating within a slot formed in the casing, and a torsionally bent spring coiled upon the first mentioned plunger and secured to said second mentioned plunger for the purpose of guiding the pin within the slot.

3. In a device of the class described, a vertically moving hollow plunger, a rubber or analogous foot mounted upon the base of said plunger, a second plunger adapted to operate within said hollow plunger, a spring interposed between said plungers, a spring coiled around said first mentioned plunger and connected to the second plunger, all operating within a cylindrical casing.

In testimony whereof I affix my signature in presence of two witnesses.

WILLIAM J. TYNON.
